UNITED STATES PATENT OFFICE.

CARL AUGUST HALLBÄCK, OF HESSLEHOLM, SWEDEN.

TWO-STROKE-CYCLE INTERNAL-COMBUSTION ENGINE.

1,279,334.

Specification of Letters Patent. Patented Sept. 17, 1918.

Application filed May 10, 1917. Serial No. 167,729.

To all whom it may concern:

Be it known that I, CARL AUGUST HALLBÄCK, citizen of Sweden, residing at Hesleholm, in Sweden, have invented certain 5 new and useful Improvements in Two-Stroke-Cycle Internal-Combustion Engines, of which the following is a specification.

This invention relates to two stroke cycle internal combustion engines, the object of 10 the invention being to provide an engine of said class having its cylinder cover placed between the piston and the crank shaft in order to make the combustion pressure upon the piston to act in a direction from the 15 crank shaft in such a way that the pounding action on the engine bed is totally avoided.

A further object is to provide an internal combustion engine running noiselessly and without shocks, and a still further object of 20 the invention is to entirely dispense with the water cooling arrangements hitherto needed for engines of this class.

With these and other objects in view, the invention consists in certain novel features 25 of construction and arrangements of parts, as will be more fully hereinafter described and pointed out in the claim.

For a full understanding of the invention and the merits thereof, reference is to be 30 had to the accompanying drawings, in which:

The figure is a central vertical longitudinal sectional view through an engine embodying my invention, parts being shown in 35 elevation, and parts broken away.

Referring to the drawing the cylinder 1 carried by the engine bed 2 is open in both ends and internally provided with an annular bottom 3 inclosing a thinner portion 4 of the piston serving as piston rod and having packing rings 5 or the like facing said portion. In the portion 4 which is hollow for the sake of cooling and open in both ends the connecting rod 6 is journaled. At 45 the upper end of the piston rod 4 and above the bottom 3 the piston 7 is fastened and fitted into the cylinder 1 with packing rings 8. On the other side of the bottom 3 another piston 9 is fastened to the piston rod 4 and 50 this latter piston is fitted into a prolongation of the cylinder 1. A feed pipe 14 for the fuel and ignition chamber 15 or the like lead to the cylinder 1 near the bottom 3 and the cylinder is also provided with an exhaust 55 opening 16 which is covered by the piston 7 but will be opened when said piston arrives

to the position most remote from the bottom 3.

The suction valve 11 is placed directly on the cylinder wall close to the bottom 3 at 60 the side of the latter nearest to the crank shaft. The working cylinder communicates with the space between the bottom 3 and the piston 9 by means of a number of grooves 17 in the surface of the piston rod 4. These 65 grooves are placed in the end of the rod nearest to the piston 9 and have such a length and are so arranged that the communication between the working cylinder and the space on the other side of the bottom 70 3 always is opened shortly after the piston during its working stroke has commenced to open the exhaust 16 or, for instance, when the piston 7 has passed half of the exhaust opening. 75

By means of this simplified arrangement the air is drawn through the suction valve 11 into the space between the bottom 3 and the piston 9 during the compression stroke and at the same time said space does not 80 communicate with the working cylinder. The air thus drawn in during the compression stroke will then be compressed during the working stroke, and when the piston 7 has commenced to open the exhaust 16 the 85 grooves 17 will open the communication between the working cylinder and the space between the bottom 4 and the piston 9 so that the compressed air passes into the cylinder and expels the rest of the exhaust 90 gases. In this way the scavenging of the cylinder will be effected very thoroughly as the air is forced to pass the entire interior of the cylinder before it escapes through the exhaust opening. The arrangement of the 95 grooves 17 in the piston rod is also adapted to cause an increased cooling of the cylinder and especially of the packing between the bottom 3 and the piston rod. Further, an engine of this type may be produced very 100 cheaply as the whole air chamber and its ports are dispensed with.

In order to reduce the possibility of the warm air reentering the passage or bore of the pistons after being expelled there-through, said passage is contracted in such manner that the increased velocity of the air while passing from the entrance to the exit will be sufficient to eject it beyond the influence of the suction created as the piston moves in the opposite direction. 110

The piston 7 may be fastened to the piston

rod 4 by means of screws or the like in order to make it easier to mount the engine.

It is evident that this type of engine may be built horizontally as well as vertically.

Having thus described the invention, what I claim as new and desire to secure by Letters Patent is:—

An internal combustion engine, comprising a cylinder having both ends open, an annular partition arranged within the cylinder near the central portion thereof and serving to divide said cylinder into a working chamber and an air chamber, an air supply valve structure leading into the air chamber upon one side of the annular partition, a fuel conduit leading into the working chamber upon the opposite side of the annular partition, hollow pistons operating within the working chamber and air cham-

ber and having outer bores of the same diameter and inner bores of different diameters, a hollow piston rod connecting said hollow pistons with its bore contracted at the end which is adjacent the piston having the smaller bore, said hollow piston having longitudinal exterior grooves which are adapted to establish communication between the air chamber and the working chamber, and a pitman connected with the hollow piston rod.

In testimony whereof, I have signed my name to this specification in the presence of two subscribing witnesses.

CARL AUGUST HALLBÄCK.
